STARTING SYSTEM FOR FREE-PISTON UNITS

Kenneth C. Cooper, Portland, Conn., assignor to
United Aircraft Corporation, East Hartford,
Conn., a corporation of Delaware

Application August 23, 1944, Serial No. 550,875

8 Claims. (Cl. 60—14)

1

This invention relates to automatic starting for free-piston units.

The copending application of Meitzler 495,927, filed July 23, 1943, discloses a starting system including an accumulator and a control valve for filling the accumulator and for causing the gas in the accumulator to enter the air spring of a free-piston unit when the desired pressure in the accumulator is reached. The gas under pressure is manually admitted to the control valve for each starting of the unit. The present invention constitutes an improvement on the disclosure of the copending application by providing for automatically controlling the admission of gas to the control valve.

A feature of this invention is an arrangement for moving the piston or pistons into starting position prior to the discharge of gas from the accumulator for starting the unit. Another feature is the interconnection of the piston moving structure with the remainder of the starting system so that the gas cannot be discharged from the accumulator until the piston has been placed in starting position.

A feature of this invention is a control system by which, if the unit fails to start on the first attempt, successive attempts will automatically be made until the unit starts or until the starting system is manually shut down.

Free-piston engine-and-compressor units are frequently used in groups as generators of gas under pressure for use, for example, in driving a gas turbine. When one or more units is operating, any of the remaining units of the group must be started under load and, therefore, require a higher starting pressure for the gas in the accumulator. A feature of this invention is an automatic control of the discharge pressure in the accumulator dependent upon the discharge pressure against which the unit must be started.

Other objects and advantages will be apparent from the specification and claims, and from the accompanying drawings which illustrate an embodiment of the invention.

Fig. 1 is a sectional view through a free-piston unit incorporating the starting device.

Fig. 2 is a diagrammatic view of a part of the starting system.

Fig. 3 is a schematic diagram of the remainder of the starting system.

Fig. 4 is a sectional view through one of the intake valves.

Fig. 5 is a diagrammatic view of the starting system.

The unit shown includes an engine cylinder 10 55

2

having reciprocating pistons 12 and 14 to which compressor pistons 16 and 18 in cylinders 20 and 22 are integrally connected. Sleeves 24 and 26 attached to the pistons complete the reciprocating piston assemblies. The sleeves in combination with stationary pistons 28 and 30 form air spring cylinders.

The piston assemblies are moved apart by the burning of fuel injected into engine cylinder 10 10 as by a device 32. Air compressed in the air spring cylinders on the power stroke returns the piston assemblies. The assemblies are always maintained at equal distances from the center of the engine cylinder by a linkage, which may 15 include racks 34 extending from the compressor pistons.

Intake manifold 38 conducts air to intake valves 40, Fig. 4, through which air alternately enters 20 opposite ends of the compressor cylinders. The compressed air leaves the cylinders through discharge valves 42, similar to valves 40 and also at opposite ends of the compressor cylinders and passes through scavenge manifold 44 through ports 46 and 48 which are uncovered by pistons 12 and 14 at the end of the power stroke, thereby 25 permitting air to be blown through the engine cylinder and exhaust ports 50 and 52 into exhaust manifold 54.

Starting devices 56 and 58 for the unit are 30 mounted in air spring pistons 28 and 30. The devices are similar and device 58 will be described in detail. Piston 30 forms a housing held within the unit by a threaded ring 60 and having an 35 accumulator chamber 62 in which gas under pressure is collected in readiness for starting. This chamber communicates with the air spring cylinder through a port 64 closed by a poppet valve 66. The stem 68 of this valve is slidable in a guide 70 on a cap 72 which closes the end 40 of chamber 62. Valve 66 closes port 64 by movement toward the storage chamber and is opened by movement away from the chamber so that pressure of gas within the chamber opens the valve. Pressure of gas in the air spring tends 45 to hold the valve closed during operation of the unit.

Cap 72 has a bore forming a cylinder 74 which receives a piston 76 on the end of valve stem 68. The inner end of cylinder 74 is connected with 50 the storage chamber by one or more ports 78. A coil spring 80 in the cylinder moves the piston toward valve closing position. A head 82 closes the outer end of cylinder 74 and is held in position by studs 84 extending through both head 82 and cap 72.

A casing 86 on head 82 has a bore 88 in which a plunger 90 is slidably. One end of bore 88 is closed by head 82, the other end by a cover plate 92. Gas under pressure is admitted to the inner end of bore 88 through a channel 94 in casing 86. With plunger 90 in the position shown, gas entering the inner end of the bore is guided into chamber 62 through a channel 96 communicating with a passage 98 in casing 86, cap 82, and head 72, and the head of piston 76 and an intersecting 10 passage 98a in the casing 86.

Passage 98a extends between and connects passage 98 and a parallel passage 99 which communicates with the outer end of cylinder 74. Passage 98a is intersected by bore 88 so that flow of fluid through passage 98a is normally cut off by plunger 90. This plunger has a groove 100, which, when the plunger is moved to the opposite end of its stroke, permits gas to flow from channel 98 into the channel 98a and through channel 99 into the outer end of cylinder 74, to cause valve 66 to open.

For moving plunger 90 to the inner end of its stroke, casing 86 has a gas inlet passage 102 which is connected by a groove 103 in plate 92 to the outer end of bore 88. When gas under pressure enters this inlet passage, it moves plunger 90 into a position to close channel 96 and to connect passages 98a and 99 to establish fluid connection between chamber 62 and the outer end of cylinder 74 the outer end of passage 98a being closed by a plug 103a, as shown. When this occurs, the pressures on opposite sides of piston 76 are balanced and the pressure on valve 66 opens the valve for the escape of gas into the air spring.

In starting the unit, gas under pressure is first admitted through channel 94 until a predetermined pressure is built up in chamber 62. After this pressure is reached, gas under pressure is admitted through passage 102 thereby moving plunger 90 to close channel 96 and to cause valve 66 to open. Before this action occurs, the piston assemblies of the unit will have been moved to starting position. The sudden inrush of air into the air springs from chambers 62 in starting devices 56 and 58 will move the piston assemblies rapidly toward each other.

The starting devices 56 and 58 may be controlled by an automatically operating valve 104 which controls the admission of gas under pressure to channel 94 and passage 102. Valve 104 includes a casing 106 having a bore in which a valve plunger 108 is mounted, the plunger being normally held in the position shown by a spring 110. The tension of spring 110 may be adjusted 40 by a nut 112 engaging threads in casing 106 to control the pressure in chamber 62 at which the starting device operates.

Casing 106 has an inlet port 114 connected to a source of gas under pressure, and an outlet port 116 connected by a conduit 118 to channel 94. Another outlet port 120 spaced from port 116 is connected by a conduit 122 to passage 102. In the normal position of plunger 108 a groove 124 in the plunger connects ports 114 and 116 and another groove 126 establishes fluid connection from port 120 to a chamber 127 at the end of casing 106. When plunger 108 is shifted to the other end of the stroke, as limited by a threaded ring 128, groove 124 connects inlet port 114 with port 120, and another groove 130 connects port 116 to a vent port 132.

For moving plunger 108, the end of casing 106 has a nut 133 with a through passage 134. Nut 133 clamps a bushing 135, the end of which forms

a valve seat engaged by the end of plunger 108. Passage 134 is connected by a branch conduit 136 to conduit 138 which connects with inlet port 114. Branch conduit 136 has an adjustable throttle valve 140 which can provide a restriction greater than any restriction from conduit 138 to chamber 62. When the desired pressure is developed in chamber 62, the pressure in passage 134 acting on the end of plunger 108 moves the plunger against the action of spring 110 to connect port 120 to inlet port 114 for procuring opening of valve 66 for starting the unit.

A small bleed passage 141 in casing 106 provides fluid connection from the end of plunger 108 to groove 130 which connects with vent port 132. This permits gas leaking past the end of plunger 108 to be vented so that the plunger will not be moved from the position shown until the desired pressure has been built up in chamber 62.

20 A passage 144 in casing 86 connects passage 99 with groove 103 in cap 92 and is closed by a check valve 146. After the starting unit has operated and conduit 122 is vented by plunger 108 returning to the position shown, gas at the right of piston 76 in cylinder 74 may escape past valve 146 so that piston 76 may move into a position for closing poppet valve 66.

25 The piston assemblies may be automatically moved to the outer ends of their stroke before the starting devices operate. The structure is the same for each piston assembly and only one of the structures will be described. Compressor piston 18 has projecting concentric sleeves 148 and 149, Fig. 3, connected at their outer ends to form a plunger 150 sliding in an annular space 151 between a sleeve 152 and a smaller sleeve 153 mounted within the unit. Only one plunger is shown, but, for purposes of balance, two oppositely placed plungers may be advantageous.

30 Gas under pressure is admitted to the left hand end of space 151 to move the piston assembly of which piston 18 is a part. A valve casing 154 has a sliding plunger valve 156 held in the position shown by a spring 158. In this position gas entering an inlet port 160 passes around a groove 162 in valve 156 to an outlet port 164 connected by a conduit 166 to the end of a bore 168 in a casing 170 at the end of sleeve 152. From bore 168 gas under pressure passes through a channel 172 in casing 170 and one or more channels 174 in head 175 on sleeves 152 and 153 to the inner end of space 151. Gas entering the end of this cylinder moves plunger 150 to the right, carrying with it the attached piston assembly and moving the piston assembly into starting position.

35 As plunger 150 moves to the right, it uncovers a port 176 connected by a conduit 178 to a passage 180 in a cap 181 in the end of casing 154. Gas entering this passage acts on the end of valve plunger 156 which is in the form of a valve 40 engaging a seat 182 in a ring 183 at the end of passage 180 and moves the plunger to the left against the force of spring 158. Inlet port 160 is then connected by groove 162 to a port 184 45 which is connected by conduit 138 to the starting release valve 104.

50 When valve plunger 156 is moved to the left, port 164 is connected by a groove 166 in plunger 156 to a vent port 188 causing a pressure drop 55 in conduit 166 and permitting a check valve in the form of a plunger 190 in bore 168 to be moved by a spring 192 to close passage 172.

55 After the engine is started, plunger 150 acts as a pump forcing gas under pressure through 60 passages 174 past a disc valve 194 and through 65

a channel 196 to a conduit 198 leading to the left hand end of casing 154. Gas may enter the space 151 through a check valve 199. Pressure entering the casing acts on the end of valve plunger 156 to return it to the position shown. While gas under pressure is being admitted to the balance pump, valve 190 is moved into a position to close passage 196. This passage is opened upon return of valve 190 to the normal position shown. During normal operation of the free piston unit, the air pumped by plunger 150 may be delivered through a passage 200 intersecting passage 196 and past a spring loaded check valve 201. The check valve 201 is so arranged that it does not open until sufficient pressure has built up in the chamber surrounding spring 158.

The supply of starting gas to the above described structure may be controlled by a starting cutoff valve. This valve includes a casing 202 having an inlet port 204 connected to a source of gas under pressure and an outlet port 206 connected by a conduit 208 to port 160 of casing 154. Between ports 204 and 206 is a valve 210 held against its seat by a spring 212 and normally preventing gas from passing between the ports. The valve 210 has a stem 214, the end of which engages a lever 216 on a shaft 218. A projecting arm 220 on lever 216 engages the end of a piston 222 in a bore 224 in casing 202. Downward movement of the piston moves the valve stem up to open valve 210.

In a bore 226 also in casing 202 is a valve plunger 228 normally held in the position shown by a spring 230 and moved downwardly by gas under pressure entering port 232 to uncover a connecting port 234 between bores 224 and 226. When port 234 is uncovered, pressure entering bore 224 moves the piston down to open valve 210 and permit the starting device to operate.

This starting cutoff valve forms the subject matter of a copending application by Meitzler, Serial No. 550,894, filed August 23, 1944, and is not a part of the present invention. It is sufficient to note for the purpose of the present disclosure, that the fluid pressure applied at port 232 is provided by a stroke indicator so arranged as to provide a high pressure when the free-piston unit is not operating. This high pressure is sufficient to move plunger 228 and set the starting system in operation immediately whenever the engine stalls.

In operation, with the parts in the position shown, the starting system is set in operation either by pressure entering port 232 or by a manual control lever 236 on shaft 218. With valve 210 open, gas under pressure passes through casing 154 and enters the end of casing 170 to move the piston assembly, of which piston 18 is a part, into starting position. As the piston assembly reaches starting position and uncovers port 176, gas under pressure passes through conduit 178 and moves valve plunger 156 to the left to connect the gas source to starting release valve 104. Gas is then supplied to the accumulator chamber and when the desired pressure in the chamber is reached, the chamber is opened and discharges gas into the air spring to start the unit.

If the unit fails to start on the first attempt, valve 156 returns to the position shown under the influence of spring 158, the space 151 having been connected by conduit 198 to the left hand end of valve 156 by the movement of plunger 156 which, by venting conduit 166, allows plunger 190 to return to the position shown. A restriction 237 in conduit 198 may be provided

for reducing the rate of pressure build up in this conduit to allow time for the starting device to operate and the gas under pressure is again directed into casing 152 and moves the piston assembly into starting position for another cycle of operation. The air in the air cushions leaks out slowly as the piston assembly moves. When the unit is started, the starting system may be rendered inoperative by the cutoff valve. This involves, as described in the above mentioned application, Serial No. 550,894, a reduction in the pressure at port 232 which permits piston 222 to move upwardly into the position shown to cause valve 210 to be closed.

When the starting system operates on one of a group of units all delivering exhaust gas to a collector, the starting pressure must be high enough to overcome the exhaust pressure. To adjust the starting pressure in chamber 62, a conduit 238, Fig. 2, connects the exhaust manifold 54 to chamber 127 at the end of plunger 108 in valve 104. The exhaust pressure added to the pressure of spring 110 increases the pressure required in the starting system before plunger 108 will be shifted to the left to cause the starting system to function.

It is to be understood that the invention is not limited to the specific embodiment herein illustrated and described, but may be used in other ways without departure from its spirit as defined by the following claims.

I claim:

1. In a starting system for free-piston units, each unit having at least one piston, and means for moving said piston in one direction into starting position, said starting system including a source of gas under pressure, a valve for admitting gas from the source to said moving means, means for admitting gas under pressure to the unit for moving the piston in the opposite direction for starting the unit, and means responsive to the position of the piston and operative when the piston reaches starting position for moving said valve to supply gas from said source to said gas-admitting means.

2. In a starting system for free-piston units, each unit having at least one piston, said system including an accumulator for storing gas under pressure and having a valve for admitting gas from the accumulator to the unit, means controlled by gas under pressure for opening the valve, and a second valve for admitting gas to the accumulator, said second valve being responsive to pressure changes in said accumulator and movable when pressure in the accumulator reaches a predetermined value for causing the first valve to open, and means controlled by the position of the piston and operative only when the piston is in starting position for admitting gas to said second valve only when the piston is in starting position.

3. In a starting system for free-piston units, each unit having at least one piston, said system including an accumulator for storing gas under pressure and having a valve for admitting gas from the accumulator to the unit, means controlled by gas under pressure for opening the valve, and a second valve for admitting gas to the accumulator, said second valve being responsive to pressure changes in said accumulator and movable when pressure in the accumulator reaches a predetermined value for cutting off the supply of gas to the accumulator and for causing the first valve to open, and means for cutting off the supply of gas to said second valve.

4. In a starting system for free-piston units, each unit having at least one piston, said system including an accumulator for storing gas under pressure and having a valve for admitting gas from the accumulator to the unit, means controlled by gas under pressure for opening the valve, and a second valve for admitting gas to the accumulator, said second valve being responsive to pressure changes in said accumulator and movable when pressure in the accumulator reaches a predetermined value for causing the first valve to open, and means responsive to the position of said piston for admitting gas to said second valve only when the piston is in starting position, and means for cutting off the supply of gas to said second valve.

5. In a starting system for a free-piston unit, having at least one piston and a plunger connected to said piston, said system including a source of gas under pressure, means for applying pressure from said source to said plunger to cause the piston to move into starting position, and means controlled by the position of the plunger and automatically operative when the piston reaches starting position for starting the unit, said automatically operative means including an accumulator for gas under pressure, and means responsive to pressure changes in said accumulator and operative when the pressure in the accumulator reaches a predetermined value for admitting gas to the unit to move the piston.

6. A starting system for a free-piston unit having at least one piston, said system including an accumulator for storing gas under pressure and having a valve for admitting gas from the accumulator to the unit for moving the piston to start the unit, pressure responsive means for causing said valve to open, means for supplying gas to said accumulator, a second valve normally in a position to admit gas to the accumulator and movable in response to pressure changes in said accumulator for procuring operation of said pressure responsive means and for cutting off said gas supplying means, and a third valve controlled by the position of the piston and operative only when the piston is in starting position for admitting gas to said second valve and thence to the accumulator.

7. A starting system for a free-piston unit hav-

5 ing at least one piston, said system including an accumulator for storing gas under pressure and having a valve for admitting gas from the accumulator to the unit for moving the piston to start the unit, pressure responsive means for causing said valve to open, a second valve controlling the supply of gas to said accumulator and movable for simultaneously cutting off the supply of gas to said accumulator and for admitting gas under pressure to said pressure responsive means, pressure actuated means for moving the piston into starting position, and valve means controlled by the position of the piston and movable when the piston is in starting position to admit gas under pressure to said second valve.

10 8. A starting system for a free-piston unit having at least one piston, said system including an accumulator for storing gas under pressure and having a valve for admitting gas from the 15 accumulator to the unit for moving the piston to start the unit, pressure responsive means for causing said valve to open, a second valve controlling the supply of gas to said accumulator and movable for simultaneously cutting off the supply 20 of gas to said accumulator and for admitting gas under pressure to said pressure responsive means, pressure actuated means for moving the piston into starting position, valve means 25 controlled by the position of the piston and operative when the piston is in starting position to cause said valve means to move for cutting off the supply 30 of gas to said piston moving means and for admitting gas under pressure to said second valve.
